(57) **CLAIM**

The ornamental design for a handle for hot air comb, as shown and described.

DESCRIPTION

FIG. 1 is a perspective view of a handle for hot air comb showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged perspective view of the handle for hot air comb of FIG. 1 as it would be positioned during use.
